PERFORATED LINER WASHER

Reuben C. Baker, Coalinga, Calif., assignor to
 Baker Oil Tools, Inc., Huntington Park, Calif.,
 a corporation of California

Application January 12, 1935, Serial No. 1,505

1 Claim. (Cl. 166—20)

This invention relates to deep oil well equipment and particularly pertains to an apparatus for washing perforated liners in deep wells.

It is the principal object of my present invention to provide an improved simple and efficient tool by means of which a perforated liner in a deep well may be quickly blanked off and washed and the tool removed from the hole.

In practice I provide a tool which may be run 10 in the hole at the end of a string of tubing. This tool is fitted with a flexible sleeve which is expanded to blank off the perforated liner by the pressure of the washing fluid conveyed through the tool so that the fluid will effect a washing 15 action exteriorly of the liner over the area of the liner so blanked off. When the fluid pressure is dropped the sleeve contracts and the entire tool may be removed from the hole.

One form which the invention may assume is 20 exemplified in the following description and illustrated by way of example in the accompanying drawing in which:

Fig. 1 is a view in centrally longitudinal section through a tool embodying the preferred form of 25 my invention and illustrating the manner of its use.

Fig. 2 is a transverse sectional view taken on line 2—2 of Fig. 1.

Referring more particularly to the accompanying drawing, 10 indicates a liner washing device principally for use in washing the exterior of a perforated liner in a well bore. This washing device may be run in the hole on tubing and used to wash the liner and then pulled from 30 the hole. In use, the device may be quickly shifted to any point along the liner so that the desired washing effect may be obtained.

From the drawing it will be noted that the device comprises a central tube 11 having a removable upper head 12 adjacent to its upper 40 end and a removable lower head 14 at its lowermost end.

It will be noticed that the upper head 12 is bored as at 15 to receive the tube 11.

To clamp the head 12 on the tube, the latter is fitted with a fixed ring 16 which fits a counterbore 17 above the bore 15 in the tube and which is adjacent the annular shoulder between the counterbore 17 and the bore 15. Packing 18 is 45 interposed between the adjacent faces of the ring 16 and the shoulder mentioned.

The upper portion of the counterbore 17 is threaded to receive a gland member 19 which is bored to receive the tube 11. When the gland 50 member is positioned the ring 16 is clamped be-

tween the gland 19 and the shoulder and thereby the parts are held relatively fixed.

It should be stated that the end of the tube above the upper head is threaded in order that it may be coupled to running in tubing. 5

The lower head 14 is formed with a central bore extending downwardly from its upper end and threaded to receive the threaded lower end of the central tube 11 and so connect the two parts. 10

A nozzle 20 is fitted to the lower head 14 in a concentric position. This nozzle 20 is cylindrical in form with a bore having a Venturi tube effect. Centrally between its ends the nozzle is fitted with an exterior flange 21 which is clamped against an annular shoulder 22 in the lower head 14 by a gland number 23. Packing 24 is provided to prevent leakage. 15

It will be noticed that the nozzle 20 extends from the interior of the tube 11 through the lower head 14 so as to discharge fluid conveyed down the tube at the lower end of the device. 20

Surrounding the central tube 11 is a flexible packing sleeve 25, the inside diameter of which is considerably larger than the exterior diameter 25 of the tube 11. This packing sleeve is fitted at its opposite ends with connector rings 26 which in turn are threaded to the upper and lower heads 12 and 14. It is intended that the sleeve be expanded by suitable fluid pressure into tight 30 contact with the inner surface of a perforated liner and when the pressure is relieved that the liner contract due to its inherent resiliency to enable the entire device to be removed from the 35 hole.

To accomplish this, the tube 11 is formed with ports 27 along its length between the heads 12 and 14. Midway between the heads 12 and 14 the interior of the tube is closed to the passage 40 of fluid by an imperforated baffle 28 so that fluid pumped into the upper end of the tube must pass into the sleeve expanding chamber 29 between the tube and sleeve before it can reach the open nozzle 20. The relative cross sectional area of 45 the nozzle bore and the tube 11 is such that sufficient pressure will be built up in the expanding chamber 29 to expand the packing sleeve 25 into firm contact with the interior surface of the liner. When the pump pressure is relieved the sleeve 25 50 will collapse and the device may be pulled from the hole.

In operation the device is constructed substantially as illustrated and the tube 11 is connected to the lower end of a string of tubing and lowered 55

into the hole. When it aligns with the section of liner it is desired to wash, fluid under high pressure is pumped down through the running in tubing into the tube 11. This fluid will pass into 5 the expanding chamber 29, expand the packing sleeve and then discharge through the nozzle. The fluid so discharged will pass out through the liner and upwardly between that section of the liner blanked off by the sleeve and bore and will 10 wash that area. By shifting the washing device any length of the liner may be washed. Also the length of the packing sleeve may be varied to effect washing of a desired length of a perforated liner in one operation.

15 After washing has been effected the pump pressure is relieved and the sleeve will contract so that the device may be pulled from the hole.

From the foregoing it is obvious that I have provided a very simple and efficient tool which 20 may be employed to expeditiously wash perforated liners in deep well bores.

While I have shown the preferred form of my apparatus it is to be understood that various changes therein may be made by those skilled in 25 the art without departing from the invention as claimed.

Having thus described my invention, what I claim and desire to secure by Letters Patent is:

An apparatus of the character described comprising a central fluid conducting tube, an upper head secured thereto, a lower head secured thereto, a nozzle in the lower head communicating with said tube, a cylindrical packing sleeve secured at its ends to said heads and arranged exteriorly about said tube, said tube having ports formed through its wall along its length between said heads, an imperforate transverse partition in said tube arranged at a point substantially centrally between said heads whereby fluid delivered downwardly through the tube will pass outwardly through said ports above said partition into the space between said tube and said packing sleeve and thence back into the tube through the ports in said tube between the partition and the lower head and then discharge through the nozzle, said nozzle having a fluid passageway considerably less in cross-sectional area than that of the tube so that the fluid between the tube and the packing sleeve will expand the latter as it seeks to discharge back into the tube and through the nozzle.

REUBEN C. BAKER.
